(57) **CLAIM**

The ornamental design for a handle, as shown and described.

DESCRIPTION

FIG. 1 is a perspective view of a first embodiment of a handle showing our new design.

FIG. 2 is a front elevational view thereof. The rear elevational view is identical thereto.

FIG. 3 is a side elevational view thereof. The opposing side elevational view is identical thereto.

FIG. 4 is a top plan view thereof.

FIG. 5 is a bottom plan view thereof.

FIG. 6 is a perspective view of a second embodiment.

FIG. 7 is a front elevational view thereof. The rear elevational view is identical thereto.

FIG. 8 is a side elevational view thereof. The opposing side elevational view is identical thereto.

FIG. 9 is a top plan view thereof.

FIG. 10 is a bottom plan view thereof.

FIG. 11 is a perspective view of a third embodiment.

FIG. 12 is a front elevational view thereof. The rear elevational view is identical thereto.

FIG. 13 is a side elevational view thereof. The opposing side view is identical thereto.

FIG. 14 is a top plan view thereof; and,

FIG. 15 is a bottom plan view thereof.

The broken lines shown are included for the purpose of illustrating the unclaimed portions of the article and form no part of the claimed design.
